James F. Duhamel,
ATTORNEY.

UNITED STATES PATENT OFFICE.

JACOB STIRISS, OF NEW YORK, N. Y.

POWDER BOX.

Application filed January 20, 1928 Serial No. 248,243.

This invention relates to powder boxes or what is known to the trade as vanity cases and its object is to provide a box comprising a container for the powder and a lid containing a mirror with locking means that will allow the box to be opened easily so that the powder is not liable to be spilled and thereby soil the clothes of the user. This consists of hooks on one member of the box that engage slots in the other member which are disengaged by turning or twisting the members on each other.

Another object of the invention is the feeding of the powder from the inside of the container to its upper side so it is accessible to the powder puff and which is an endless band arranged to pass down into the container to gather up the powder and convey it to the outer surface of the top of said container.

20 A further object of the invention is to provide means for readily supplying the container with powder by hinging to its top a frame carrying the endless band so that the said frame may be thrown up exposing the opening into which it is adapted to operate.

Another object attained by the invention is means for filling the container and consisting of a door in its top to be lifted to afford access to same.

30 These and other objects and details of the invention are more fully described in the following specification, set forth in the appended claims and illustrated in the accompanying drawings, wherein:

35 Figure 1 is a plan view of the improved powder box.

Fig. 2 is an edge view thereof.

Fig. 3 is a plan view of the device with the lid open and the box partly in section.

40 Fig. 4 is a vertical sectional view through the lines 4-4 of Fig. 3.

Fig. 5 is a perspective view of the belt carrying frame.

45 Fig. 6 is a modified form of the sliding hinge.

Fig. 7 is another form of the locking hook.

Vanity boxes of this nature as heretofore constructed have been so locked or fastened when closed that the effort to open same often injures the finger or breaks the finger nail of

the party so attempting and results in such violent agitation of the box that the powdered contents is apt to be shaken over the clothes of the possessor, and in dispensing the loose powder the common practice is to confine the powder within a perforated lid and to feed the powder through same. These perforations wear the feeding means and the puff to shreds in a short time.

To overcome these objectionable features 60 the present invention comprises a box, preferably circular, of two parts 10 and 11, the former being the container for the powder and the latter is the lid. The edges of these two members are knurled or roughened to 65 facilitate the rotation of the two on each other and the lid 11 has several hooks 12 depending therefrom and offset towards the inside of the same and the edge is rolled in and a ring 11' is used to secure the mirror 13. 70

The box 10 has slots 14 cut in its side to correspond with the hooks 12 and at the side of each of these slots is a loop or eye 15 into which the offset end of its adjacent hook enters thus holding the abutting edges of the 75 members together and locking the lid on the box.

Secured to the lid at its edge is the hinge 16 whose other hinge member is a flexible segmental strip 17 playing within the box 80 while the hinge passes through a slot 18 in said box. This slot is punched from the edge of the box and the portion 19 of the slot acts as a guide for the hinge member 17.

The hinge 16 and the hooks 12 are therefore all free to move in their respective slots and the lid and box may be rotated on each other to lock or unlock them so the lid may be raised and access had to the powder.

The powder is contained in a compartment 90 20 within the box 10 whose edge 21 is turned in to secure the walls of said compartment and to cover the space between these two members and prevent any leakage of the powder out of the slots 14. In the top of the 95 compartment is an opening 22 and hinged in the same on the pintle 23 is a frame 24 carrying on the side opposite the pintle a rod 25 to support the frame in its opening. The frame 24 has an upper flat surface and its flexible 100

ends 26 are bent downward and towards each other with the extremities bent inward. This frame carries an endless band 27 of felt, plush or similar fabric which comes in contact with the powder at the bottom of the compartment 20 and carries said powder to the outside of the compartment and box and on the upper face of the band so that a limited amount may be gathered up by the puff.

10. There is sufficient resiliency in the frame 24 to exert an outward pressure on the band to take up slack, at the same time permit movement by the finger of the user of the box, and the clamps for pintle 23 and rod 25 guide the band and prevent its dislodgement from the frame.

15. There is also an opening at one side of the top of compartment 20 that is covered by a flap-door 20' through which the powder container may be replenished.

20. The frame 24 may be held down by the rod 25 being shoved into a socket 25' indented on the top of compartment 20 and the frame may be raised by means of the lip 24' while the door 20' may be raised by a similar lip 20'.

25. In Fig. 6 a spring wire 30 is shown as being rigidly secured to the lid 11 by the clamp 31 that plays in the slot 32 so that the lid may be shifted while the wire lies under the edge 21. Fig. 7 also shows a modified hook connection where the hook 12' fits into a socket formed by punching the wall of the box 10 outward as at 33, and inward as at 34, so that the depression and hole at the junction of 33 and 34 will permit the hook to engage the box when the lid is closed and turned.

30. This improved powder box thus provides against loss of powder and the spilling of the same over the party attempting to open the box as by the simple rotation of the box and cover permits of the raising of the lid without jolt or jar, thus permitting the powder to remain in the box.

35. The minimum of space around the dispensing band also affords a protection against waste and the raising of the band frame or door 20' permits the replenishing of the box with powder or the return of any that may have found its way to the top of the container and that has not been mopped up by the powder puff. The location of the ring 11 against the bead on the top of container also prevents leakage and waste of powder.

40. It is obvious that other alterations or modifications of the parts may be resorted to without departing from the essential features above described or from the scope of the appended claims.

45. What I claim as new is:—

1. In a powder box, the combination of a box comprising a containing section and a lid, a hinge connecting the container section

and the lid, and means adapted to lock the lid 65 in closed position when the said container section and lid are rotated with relation to each other.

2. In a powder box, the combination of a box of two sections, a hinge connecting the 70 two sections, means adapted to allow the hinge to shift with relation to one of the sections, and means for locking the two sections together when the sections are rotated on each other.

3. In a powder box, the combination of a box comprising two sections, a hinge secured to one section and shiftable in the other section, and hooks from one section adapted to engage the other section when one of the sections is rotated on the other.

4. In a powder box, the combination of a box comprising a container, an endless band adapted to feed the powder from the container, a lid, a hinge secured to the lid and slidably connected with the container, and engaging means adapted to lock the container and the lid together when one is rotated with relation to the other.

5. In a powder box, the combination of a 90 box comprising a container having a top, an endless band playing through an opening in said top, a lid, a hinge secured to the lid and slidably connected to the container, and depending hooks from the lid adapted to engage securing means in the container when one of the box members is rotated with relation to the other.

6. In a powder box, the combination of a 100 box comprising a container for a powder and having a cover with an opening, a frame having flexible ends and carried in the opening, an endless band adapted to move around the frame and enter the powder in the container, 105 a lid for the box, a hinge connecting the lid and the container and allowing them to rotate on each other, and locking means actuated by the rotation of the container and lid.

7. In a powder box, the combination of a 110 box comprising a container and having slots in its outer edge, a lid adapted to impinge the box, a hinge secured to the lid by means of one member, a flexible strip carried by the other member of the hinge and slidable within the box, a top to the container and having an opening, a hinged frame in the opening and adapted to carry a flexible band, and locking means on the lid and playing in the slots of the box.

8. In a powder box, the combination of a 120 box section having a powder container and with slots around its edge, a top to the container and having an opening, a frame hinged in the opening, a flexible band adapted to travel around the frame, a lid, a hinge playing through a slot in the box and secured to the lid, a strip constituting the other member of the hinge and slidable in the box, and

hooks playing in the other slot and adapted to lock the lid and box together.

9. In a powder box, the combination of a container for powder, a lid revolvable about the same, locking means for the container and the lid, a top for the container and having openings, a band-carrying frame in an

opening, a flap-door in another opening, a mirror in the lid, and a ring in the lid adapted to secure the mirror and to make contact with the container top. ¹⁰

In testimony whereof I hereunto affix my signature.

JACOB STIRISS.
